UNITED STATES PATENT OFFICE.

ELERT A. HILL, OF LOS ANGELES, CALIFORNIA.

LOCK.

Application filed April 1, 1922. Serial No. 548,770.

To all whom it may concern:

Be it known that I, ELERT A. HILL, a citizen of the United States, residing at Los Angeles, in the county of Los Angeles and 5 State of California, have invented new and useful Improvements in Locks, of which the following is a specification.

My invention, herein set forth, pertains to a keyless lock and especially relates to the 10 type of lock embodying a latch and knob such as is particularly applicable for use on the doors of buildings.

An object of this invention is to provide a keyless lock which may be mounted in a 15 door knob and operated to place the knob in or out of a latch actuating position, and by means of which retraction of the latch by the lock bearing knob may be inhibited.

Another object is to provide a construction in a lock of the above character whereby the parts may be readily constructed and assembled, and whereby the keyless lock may be operated as a combination lock as by depressing a plurality of push pins one or 25 more times, and in which the combination of the lock may be readily changed.

Another object is to provide a combined latch and combination or permutation lock for doors in which the door will be in a 30 locked condition on one side and in unlocked condition on the other side.

With the foregoing objects in view, together with such other objects and advantages as may subsequently appear, my present invention resides in employing the parts, or their equivalents, and the combination and arrangement of parts hereinafter described and claimed, and illustrated in the accompanying drawings, in which:—

40 Figure 1 is a view in section and end elevation of a door-lock.

Fig. 2 is a detail in section and elevation as seen on the line 2—2 of Fig. 1.

Fig. 3 is a view in cross section showing 45 a modified form of the invention.

Fig. 4 is a detail end elevation of the lock carrying knob with the lock removed.

Fig. 5 is a view in section as seen on line 5—5 of Fig. 4.

50 Fig. 6 is a view in section as seen on line 6—6 of Fig. 4.

Fig. 7 is a view in section as seen on line 7—7 of Fig. 3.

Fig. 8 is an end view of a rotary tumbler.

Fig. 9 is a perspective view of a combination reminder.

More specifically 10 indicates the casing of a door-lock which is fitted with a latch 11, a bolt 12, a transverse shaft 13 for operating the latch, and inner and outer knobs 14 and 15 respectively for turning the shaft, the outer knob being normally in such relation to the shaft and catch that it may be turned without actuating the catch or bolt. The outer knob is hollow and is fitted with a keyless lock 16 by which this knob or the shaft may be placed in operative relation to the latch.

In the form of the invention shown in Figures 1 and 2, the knobs are engaged with the shaft and the latter is moveable longitudinally in respect to the knobs to throw it in and out of operative relation to either the latch or bolt and the outer knob is connected to the shaft at all times, while in the modified form shown in Fig. 3, the inner knob is fixed on the shaft which is always in operative relation to the catch, and the outer knob is adapted to be thrown in and out of engagement with the shaft.

The outer knob 15 is fitted with a hub 17 which bears in a collar 18 on the lock casing and is formed with a peripheral channel 19 engaged by a pin or screw 20 on the collar to hold the knob 15 against longitudinal movement, yet permit its being rotated. The inner knob is provided with a hub 21, which, when the shaft is reciprocal, bears in a collar 22 on the lock casing and is formed with a peripheral channel 24 engaged by a screw 25 on the collar to hold the knob 14 against longitudinal movement yet permit rotation thereof; but where the shaft is not designed to reciprocate the hub is secured thereto by a screw 26 as shown in Fig. 3.

In the application of the invention, as shown in Figs. 1 and 2, a collar 27 is mounted on shaft 13 and has a finger 28 thereon adapted to be aligned with a pair of studs 29—30 on the bolt 12, or positioned to engage a dependent arm 31 pivoted on the latch 11 which is offset in relation to the studs 29—30. When the finger is aligned with the arm, the shaft may be rotated to dispose the finger in front of the arm to retract the latch in opposition to a spring 32; the arm bearing against a shoulder 33 on

the latch during this operation, but on rotating the shaft in an opposite direction the finger will rock the arm and pass freely therebeneath without operating the latch, which is normally maintained in its forward position by the spring 32. When it is desired to actuate the bolt the shaft 13 is moved longitudinally to align the finger 28 and studs 29—30 whereupon on rotation of the shaft the finger may engage stud 29 to advance the bolt or engage stud 30 to retract the bolt.

Any suitable means may be employed for effecting engagement between the shaft 13 and knobs 14 and 15 whereby the shaft may be moved longitudinally in the knobs and yet remain in rotative engagement therewith, but which is here shown as accomplished by forming the shaft square and providing the hubs of the knobs with square openings to receive the shaft.

The shaft is normally disposed in its latch operating position by means of a spring 34 which bears between the hub 17 and a flange 35 on the shaft.

As a means for enabling a person to effect longitudinal movement of the shaft from the inside of the door, the inner end of the shaft is fitted with a head 36 projecting through the knob, which has a shoulder 37 to abut against the knob to limit outward movement of the shaft under action of the spring 34.

In the form of the invention shown in Fig. 3, a collar 38 is fixed on the shaft 13 and has a finger 39 arranged in operative relation to a stud 40 on the latch 11; the shaft being held against longitudinal movement by a pin 41 on the casing 10 extending into a peripheral channel 42 on the shaft. The outer end of the shaft is formed with a channel 43 to receive a tongue 44 on a slide-bar 45 mounted in the hub for longitudinal reciprocal movement and held against rotation relative to the knob. A spring 46 is arranged to act on the bar and normally hold the tongue out of engagement with the slot. The lock bolt 12 shown in the drawing in Figure 3 may be operated by a key in the manner common to door locks, or may be eliminated, as the operation of the bolt 12 is not affected by the lock mechanism controlling the latch bolt 11.

It will now be seen in the arrangement shown in Fig. 1, that when the shaft 13 is in its normal advanced position the latch may be operated by turning either the inner or outer knobs and that the bolt 12 cannot be operated without first retracting the shaft 13 to position the finger 28 in alignment with the studs 29—30 on the bolt, and that by the arrangement shown in Fig. 3, the latch 11, which also serves as a lock-bolt, cannot be operated by the outer knob without first retracting the slide-bar 45.

Means are provided controlled by the keyless lock, whereby retraction of the members 13 or 45 may be manually effected from the outside of the door to unlock the latter by turning the knob 15, which means embodies a disk 47 mounted in the knob to have combined rotary and longitudinal movement relative thereto.

The mounting of the disk embodies a pair of oppositely inclined flanges 48—49 projecting inwardly from opposite sides of the knob on the outer sides of which the inner face of the disk seats.

The circumferential periphery of the disk bears on an annular wall formed on the knob, a flange 50 on the disk being adapted to abut against a shoulder 51 on the knob to limit inward movement of the disk. To advance or retract the disk in relation to the knob, screw engagement is effected between the disk and knob by means of a bolt 52 extending transversely through a projection 53 on the inner face of the disk which bolt protrudes at its ends alongside of the inner faces of the inclined flanges 48—49, as shown in Figs. 1 and 3; the ends of flanges being spaced apart to permit the bolt being passed from the outer to the inner sides thereof. It will now be seen that on turning the disk in one direction the bolt in riding on the inclined flanges will act to advance the disk inwardly so that the projection 53 on the disk which bears against the outer ends of the shaft 13 or bar 45 will act to advance the shaft or bar in opposition to the springs 34 or 46.

Means are provided for effecting a locking engagement between the bolt and the knob to fasten the disk against rotation either in its advanced or retracted position, and embodies serrations 54 and 55 formed on the knob adjacent the undersides of the flanges 48 and 49; the projections 56 of the serrations 54 being arranged diametrically opposite the depressions 57 of the serrations 55 so that when one end of the bolt rides over a projection 56 the bolt will be moved lengthwise so that its other end will extend into a depression 57. By locking the bolt in this position the disk will be held against turning. For this purpose I preferably employ a push-pin controlled locking mechanism set forth in and constituting the subject matter of an application for United States Letters Patent, filed February 14, 1922, Serial Number 536,581.

This locking mechanism includes a series of rotary tumblers 58 mounted to rotate on the bolt 52 having ratchet teeth 59 on their peripheries engaged by spring pressed catches 60 on spring pressed push-pins 61 in such fashion that on depression of a push-pin a tumbler will be turned a partial revolution.

The bolt is formed with longitudinal

groove 62 and has a series of circumferential channels 63, and mounted on each tumbler is a spring pressed pin 64 which rides in a channel 63 and is adapted to be positioned in alignment with the groove to permit longitudinal movement of the bolt under action of a spring 65. When all the tumblers are arranged with the pin 64 in alignment with the groove the bolt is free to move in either direction, but when one of the pins is out of alignment with the groove the bolt will be locked. A certain number of impulses must be imparted to each tumbler from a starting position to dispose the pins in the groove aligned position. To determine the starting position, a spring pressed indicator pin 66 is arranged in the disk and positioned to be actuated by each ratchet tooth as the tumbler is rotated. A filler 67 is provided to extend into a recess between adjacent ratchet teeth to effect a lesser movement of the pin so that the position of the filler may be readily ascertained, which filler is so disposed as to indicate the starting position.

As a means for reminding a person of the combination of impulses that are to be given the several push-pins to unlock the bolt 52, I provide the device shown in Fig. 9, which comprises a casing 68 containing a series of pins 69 mounted to rotate and held against longitudinal movement, which pins have screw threaded portions engaging sleeves 70 formed with points 71 extending through the slots 72 in the casing. Numbered graduations 73 are arranged at the sides of the slots which are indicated by the pointer. When the combination of the lock is ascertained the pins 69 are turned to dispose the pointers adjacent the graduation bearing the number corresponding to the number of the combination. This device can be carried on the person or placed in a convenient place, so that if the combination of impulses is forgotten, it is readily determined by glancing at the numbers indicated by the pointers in the slots.

The operation of the invention is apparent from the foregoing, it being seen that on turning the disk to move it inwardly the outer knob will be thrown into operative relation to the door-lock in which it may be maintained by locking the disk in its innermost position so that on turning the knob 15 the door may be unlocked. When the disk is in its outermost position the outer knob will be out of operative relation to the door lock and accordingly the lock cannot be unlocked from the outside of the door.

60 I claim:

1. In a lock, door locking means, a knob for operating said door locking means to unlock the lock, means whereby the knob is normally disposed out of operative relation to said door locking means, a rotary element

on said knob, means whereby turning said element in relation to said knob will position the knob in operative connection with the door locking means whereby on turning the knob the door may be unlocked, and a lock 70 carried by said rotary element for locking it in either an operative or inoperative position.

2. In a lock, door locking means, a knob for operating said door locking means to 75 unlock the same, normally out of operative connection with said door locking means, a disk mounted on said knob, means whereby rotation of said disk will cause it to move inwardly or outwardly on the knob, said disk operating on its inward movement to place the knob in operative connection with the door locking means, and means for locking the disk in either its inner or outer positions. 80

3. In a lock, door locking means, a knob for operating said door locking means to unlock the same, normally out of operative connection with said door locking means, a disk mounted on said knob, means whereby rotation of said disk will cause it to move inwardly or outwardly on the knob, said disk operating on its inward movement to place the knob in operative connection with the door locking means, and means for locking the disk in either its inner or outer positions, 85 a bolt carried on said disk engageable with the knob, and means for locking the bolt in its knob engaging position. 90

4. In a door lock, door locking means, a knob for operating the door locking means to unlock same normally out of operative connection therewith, a reciprocal member slidably carried by said knob and held against rotation relative thereto adapted on being advanced to effect operative connection between the knob and the door locking means, a spring acting to yieldably hold said reciprocal member in a retracted position, a rotary disk carried by said knob, and means whereby rotation of said disk will act to advance the reciprocal member in opposition to said spring. 100

5. In a lock, door locking means, a knob for operating the door locking means to unlock same normally out of operative connection therewith, a reciprocal member slidably carried by said knob and held against rotation relative thereto adapted on being advanced to effect operative connection between the knob and the door locking means, a spring acting to yieldably hold said reciprocal member in a retracted position, a rotary disk carried by said knob, means whereby rotation of said disk will act to advance the reciprocal member in opposition to said spring, and means for locking said disk 115 against rotation. 120

6. In a lock, door locking means, a knob for operating said locking means and nor-

- 5 mally out of operative connection therewith, a rotary disk carried by said knob, inclined flanges on said knob, a bolt on said disk 20 slidably engaging said flanges whereby on turning said disk the latter will be caused to advance, and means whereby advance 25 movement of the disk will operate to place the knob in operative connection with said locking means.
- 10 6. In a lock, door locking means, a knob for operating said locking means and normally out of operative connection therewith, a rotary disk carried by said knob, inclined flanges on said knob, a bolt on said disk 30 slidably engaging said flanges whereby on turning said disk the latter will be caused to advance, and means whereby advance movement of the disk will operate to place the
- 15 knob in operative connection with said locking means, and means for locking said bolt 20 against movement relative to the knob.
8. In a lock, door locking means, a knob for operating said locking means and normally out of operative connection therewith, a rotary disk carried by said knob, inclined flanges on said knob, a bolt on said disk 25 slidably engaging said flanges whereby on turning said disk the latter will be caused to advance, and means whereby advance 30 movement of the disk will operate to place the knob in operative connection with said locking means, a series of push pins carried by said disk, and means controlled by said push pins for locking the bolt against movement relative to the knob.

ELERT A. HILL.
